UNITED STATES PATENT OFFICE.

MAURICE SHAPIRO, OF NEW YORK, N. Y.

DESIGN FOR A SHEET-MUSIC CABINET.

No. 39,923.

Specification for Design.

Patented April 20, 1909.

Application filed January 19, 1909. Serial No. 473,197. Term of patent 14 years.

To all whom it may concern:

Be it known that I, MAURICE SHAPIRO, a citizen of the United States, residing in the city, county, and State of New York, have invented a new, original, and ornamental Design for Sheet-Music Cabinets, of which the following is a specification, reference being had to the accompanying drawing, forming part thereof.

The figure is a perspective view of sheet music cabinet showing my new design.

I claim:—

The ornamental design for a sheet music cabinet, as shown.

MAURICE SHAPIRO.
